Primary Examiner — Steven J Czyz*(74) Attorney, Agent, or Firm* — Wilson Sonsini Goodrich & Rosati**CLAIM**

The ornamental design for a smart health management device, as shown and described.

DESCRIPTION

FIG. 1 is an isometric view of a smart health management device;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of smart health management device, shown in an open state and in use with environment. The broken lines depict portions of the article that form no part of the claimed design.
